POWER-OPERATED SEDIMENT TESTER

Adam M. Lang, Indianapolis, Ind., assignor to
 Langsenkamp Wheeler Brass Works, Inc.,
 Indianapolis, Ind., a corporation of Indiana

Application July 22, 1944, Serial No. 546,149

7 Claims. (Cl. 73—53)

This invention relates to a power operated sediment tester and has for a primary object a provision of means for taking samples of fluid, such as milk for example, one sample right after another in quick order without undue expenditure of energy upon the part of the operator to the end that the milk containers may be readily passed along for emptying, all without undue delay.

In order to grade milk, it has been found necessary to take sediment tests thereof, and these tests are generally made at the incoming unloading dock at a central point where milk cans are taken from a truck and placed upon a dock or on conveyors carrying the individual cans into the processing plant. In a large plant, a great number of cans are received each morning and must be handled readily. Heretofore sediment tests have been taken by hand operated devices requiring considerable time and also the expenditure of quite a bit of energy upon the part of the operator whereby the taking of the samples became quite tedious and odious.

A further object of the invention is to provide an extremely simple structure which will not only be positive and quick acting but will also present the minimum parts for cleaning and handling after the samples have been taken.

A further advantage of the invention resides in the fact that no fluid, the sample of which is to be taken, flows into any of the valve structure employed in operating the device. These and many other objects and advantages of the invention will become apparent to those versed in the art in the following description of one particular form of the invention as illustrated in the accompanying drawings, in which

Fig. 1 is a view in side elevation and portional section of a structure embodying the invention;

Fig. 2, a view in central vertical section through the upper end of the structure on an enlarged scale on the line 2—2 in Fig. 1;

Fig. 3, a view in top plan of the complete assembly embodying the invention;

Fig. 4, a view in central vertical section through the valve head on an enlarged scale with the intake or vacuum valve operated viewed on the line 2—2 in Fig. 1;

Fig. 5, a similar view with the pressure or outlet valve operated;

Fig. 6, a view in front elevation of the valve head;

Fig. 7, a view in transverse section on the line 7—7 in Fig. 6; and

Fig. 8, a view in side elevation of a valve plug 55

rotated counter clockwise 90 degrees from the position shown in Figs. 2, 4 and 5.

Like characters of reference indicate like parts throughout the various views in the drawings.

5 An elongated tube 10, preferably transparent, has a lower fitting which is attached thereto to which is detachably secured an intake thimble 12. This thimble 12 carries across its upper end a relatively fixed screen 13 on which is placed a filter disk 14 under the diametrically positioned bar 15. The structure at the lower end of the tube 10 thus far described is similar to that as shown and described in my U. S. Letters Patent No. 2,153,894, issued April 11, 1939. Secured to 10 the upper end of the tube 10 is a head generally designated by the numeral 16, and from this head extends a handle 17 to the end of which are attached the vacuum or inlet pipe 18 and the pressure or discharge pipe 19 of a pump 20 that 15 is integrally mounted on the end of an electric motor 21. The details of the pump 20 do not form a part of the invention per se and are therefore not shown, particularly since the motor and pump unit may be bought commercially.

20 In the head 16 is a pair of spaced apart vertically aligned bores 22 and 23 within which are slidably fitted valve plugs 24 and 25 respectively. The bores 22 and 23 are intercepted by a transverse bore 26 extending entirely across through the head 16 to open from each side thereof. Then below this transverse bore 26 is another transverse bore 27 which leads from the bore 22 to the bore 23, being closed to any external side opening. Centrally of the bore 27 is a vertical bore 28 which extends downwardly to open into a larger screw-threaded bore 29, which in turn opens through the underside of the head 16.

25 Behind the bore 27 in parallel axial alignment therewith is a by-pass bore 30, Fig. 3, which has no opening externally of the head 16 but does have openings from each of the bores 22 and 23. Each of the valve plugs 24 and 25 is normally urged to an upper position by the respective springs 31 and 32 which bear against the lower ends of the bores and enter bores within the respective plugs to bear against upper ends thereof. To limit the upper travel of these two plugs, bushings 33 and 34 are respectively screw-threadedly 30 entered into the upper ends of the bores 22 and 23. For convenience in operating, each of the plugs 24 and 25 has respectively attached to its outer upper end buttons 35 and 36 having pins screw-threadedly entered axially into the plugs, these buttons being removed to permit insertion

of the bushings 33 and 34 into their respective bores.

In order to prevent axial rotation of the valve plugs 24 and 25, screws 37 and 38 are screw-threadedly carried by the head 16 to enter from the outside thereof and have pilot ends, Fig. 7, enter vertically disposed slots along the outer sides of the plugs, the fit between being sufficiently loose to permit free vertical traveling of the plugs within their respective bores. The valve plug 24 is provided with a diametrically transverse bore 39 which may register with the bore 26 when that plug is pushed into its down or operating position for intake of fluid into the cylinder 10. The plug is provided with a port 40 spaced below the bore 39 to register with the bore 27 simultaneously with registration of the bores 39 and 26. A port 41 90° around from the port 40 simultaneously registers with a head intake or vacuum passageway 42. This passageway 42 in turn communicates with a passageway 43 through the handle 17 to discharge into the vacuum pipe line 18. Below the port 41, and 180° therearound, the plug 24 is provided with a port 44 to register with the opening into the by-pass bore 30 when the valve plug 24 is in its uppermost position as shown in Figs. 3 and 5. Also in axial alignment and on the opposite side of the plug 24 is a port 45 registering with the head passageway 42 when the plug is in its uppermost position, Figs. 3 and 5.

Furthermore, when the plug 24 is in the uppermost position, the transverse bore 39 is closed off at both ends by being within the bore 22 above the head bore 26 and the port 40 then registers with the bore 26 while the other or opposite side of the plug closes off that bore in respect to outward opening from the body.

The plug 25 identical with the plug 24 is provided with an upper transverse bore 46 which, Fig. 5, with the plug in a down position, will register with the bore 26 to provide a continuous passageway across through the plug. Also when the plug 25 is down, a side port 47 in the plug 25 registers with the head bore 27 while another port 48, 90° around registers with the opening into the by-pass bore 30. Then when the plug 25 is in its upper normal position, Fig. 4, its transverse bore 46 is closed off; the port 47 registers with the bore 26 with the opposite side of the plug closing the bore to outward discharge; the port 48 is closed off by the wall of the bore 23; and oppositely positioned ports 49 and 50 provided in the plug 25 register with openings respectively from the head intake passageway 51 and the head by-pass bore 30. This head passageway 51 communicates with a passageway 52 through the handle 17 with which the pressure pipe line 19 connects.

With both valve plugs 24 and 25 in their uppermost positions as indicated in Figs. 2 and 3, the pump 20 operates in a normal closed cycle wherein in the pump simply circulates air from the pressure side through the passageway 52, across the valve plug 25, through the by-pass 30 and back through the valve plug 24, passageways 42 and 43 and the vacuum line 18. With a filter disk 14 placed in position as above described, the operator manipulates the device by holding the handle 17 in his hand and inserting the thimble 12 into the fluid to be sampled, such as within a milk can, and then pushes down on the intake or vacuum valve button 35 to leave the other button 36 alone. Then, Fig. 4, the by-pass 30 is closed off and air is pulled up through the head

bore 28; through the port 40 into the bore of the plug 24; back through the port 41; head passageway 42; handle passageway 43; and pump intake line 18 to the pump 20. The pump 20 discharges through the line 19, handle passageway 52; head passageway 51; valve plug port 50; up through the plug 25; through the port 47; across through the bore 26; valve plug bore 39; and into the atmosphere from the outlet of the bore 26.

The button 35 is held down and the air is exhausted from the cylinder 10 in the manner just stated until the desired quantity of fluid is pulled into the cylinder 10. While this might be done by allowing the fluid to rise within the tube to a predetermined mark, the level of the fluid is automatically controlled by a float device.

This float device consists of a float 55 guided by a lower extending pin 56 in a transverse bracket 57 carried at the lower end of an inserted cylinder 58, the upper end of which is engaged in any suitable manner herein shown as screw-threadedly on a disk 59. This disk 59 is held against the underside of the head 16 within the cylinder 10 by means of a valve holder 60 which has a screw-threaded end engaging within the bore 29 of the head 16. This valve member 60 has a central bore therethrough and carries on its lower end a cylinder 61 within which is positioned loosely a metal ball 62. A guide 63 in the lower end of the cylinder 61 receives a pin 64 extending upwardly from the float 55 and is of that length whereby the float will lift the ball 62 and seat it against the lower end of the bore through the valve member 60 when the float 55 has been lifted by the rising fluid in the cylinder 10 to the predetermined level. By closing off the bore in the valve member 60 the vacuum line to the pump 20 is thereby intercepted or closed off. Also by closing off the bore at the lower end of the valve member 60, none of the fluid may enter into the passageways and valve structures of the head 16.

To obtain the sediment from the sample of fluid drawn into the cylinder 10, the fluid is expelled from the cylinder 10 through the filter disk 14, this disk 14 having been lifted to permit the fluid to flow upwardly and therearound as the fluid enters the lower end of the cylinder 10.

When the fluid has reached the predetermined level in the cylinder 10, which can readily be determined by the operator by the pulsation or jerk as the ball 62 seats itself, the valve button 35 is released and the valve button 36 is pushed down whereby the valve plugs assume those positions shown in Fig. 5. Then the by-pass 30 is closed off by the valve plug 25 and air from the pressure side of the pump 20 travels through the line 19; handle passageway 52; head passageway 51; port 48 of the plug; through the plug 25 out the port 47; passageway 27; and discharges through the vertical bore 28 down through the valve member 60 to blow the fluid on out of the cylinder 10.

To provide an intake for the pump 20 to permit this pressure flow, air enters the bore 26, Fig. 5, travels through the valve plug bore 46, across the bore 26 and enters the port 40; and then down through the plug 24 to discharge through the port 45; through the head passageway 42; handle passageway 43; and pump intake line 18.

When all of the fluid has been expelled the button 35 is released and the pump 20 is allowed to run if desired while the filter disk 14 is being removed by detaching the lower thimble 12, then a new filter disk inserted for the next test. With

both buttons 35 and 36 in their uppermost positions as indicated in Figs. 2 and 3, the passageway 27 is closed off by the valve plugs 24 and 25 and the air simply circulates from one side of the pump to the other as above indicated through the opposite ports in each of the valve plugs providing communications with the by-pass bore 30. In the present showing of the invention, the bore 27 and the by-pass 30 are formed by boring into the side of the head 16 and then plugging up 10 the outer ends with screw plugs 65 and 66.

The cylinder 10 is preferably detachably connected with the head 16 in any suitable manner whereby the cylinder may be removed for cleaning purposes when desired and likewise the cylinder 58 may be detached to permit cleaning of the float 55 and its surrounding cylinder.

It is, therefore, to be seen that I have provided an exceedingly simple mechanism for controlling in and out flows of fluids into the sampling cylinder simply by the manipulation of control buttons and that the control mechanism is not subjected to the fluids being sampled.

While the invention has been herein shown in the one particular form as described, it is obvious that structural changes may be embodied particularly in the boring of the head and the shape of the valve plugs, all without departing from the spirit of the invention, and I, therefore, do not desire to be limited to that precise form beyond the limitations as may be imposed by the following claims.

I claim:

1. In a fluid sediment sampling device, the combination of a fluid receiving receptacle having a lower end intake opening; a head to which the receptacle is attached; an air pump having intake and outlet conduits connecting with said head; said head having passageways therethrough normally closed to said receptacle and in communication with said conduits whereby said pump may operate to circulate air in a closed system; intake valve means in said head intercepting said passageways; said head having a passageway leading from said receptacle to said valve means; and all of said passageways being arranged in said head to direct discharge from said pump through and externally of said head and receptacle and to provide a pump intake flow from said receptacle when said valve means is shifted from said closed system condition.

2. In a fluid sediment sampling device, the combination of a fluid receiving receptacle having a lower end intake opening; a head to which the receptacle is attached; an air pump having intake and outlet conduits connecting with said head; said head having passageways therethrough normally closed to said receptacle and in communication with said conduits whereby said pump may operate to circulate air in a closed system; intake valve means in said head intercepting said passageways; said head having a passageway leading from said receptacle to said valve means; and all of said passageways being arranged in said head to direct discharge from said pump through and externally of said head and receptacle and to provide a pump intake flow from said receptacle when said valve means is shifted from said closed system condition; and pressure valve means in said head intercepting said passageways to direct flow from said pump into said receptacle upon said intake valve means being in its normal position for said closed system and said pressure valve is shifted from the closed system condition.

3. In a fluid sediment sampling device, the combination of a fluid receiving receptacle having a lower end intake opening; a head to which the receptacle is attached; an air pump having 5 intake and outlet conduits connecting with said head; said head having passageways therethrough normally closed to said receptacle and in communication with said conduits whereby said pump may operate to circulate air in a closed system; intake valve means in said head intercepting said passageways; said head having a passageway leading from said receptacle to said valve means; and all of said passageways being arranged in said head to direct discharge from said pump through and externally of said head and receptacle and to provide a pump intake flow from said receptacle when said valve means is shifted from said closed system condition; and means automatically closing off said receptacle passageway upon fluid reaching a predetermined height in said receptacle as induced by flow in said system upon shifting of said intake valve means.

4. For checking sediment in fluids, a fluid 25 sampling receptacle having means at its lower end for entrance therein of the fluid and filter means through which the fluid is discharged; a head attached to the receptacle and having normally a passageway thereacross; an air pump 30 having intake and discharge connections in spaced apart relation with said passageway, whereby said pump may operate in a closed system through the passageway; a second passageway across said head having communication with said receptacle; intake and pressure control valves intercepting both of said passageways respectively between said intake and discharge connections of the one and on each side of said receptacle communication of the other; said first 40 passageway opening to the atmosphere beyond said valves; and each of said valves carrying passageways thereacross to register in different valve positions with said passageways, to provide an open passageway from said pump intake connection through the head to said receptacle and simultaneously a passageway from said pump discharge connection to the atmosphere.

5. For checking sediment in fluids, a fluid 50 sampling receptacle having means at its lower end for entrance therein of the fluid and filter means through which the fluid is discharged; a head attached to the receptacle and having normally a passageway thereacross; an air pump having intake and discharge connections in spaced apart relation with said passageway, whereby said pump may operate in a closed system through the passageway; a second passageway across said head having communication with said receptacle; intake and pressure control valves 55 intercepting both of said passageways respectively between said intake and discharge connections of the one and on each side of said receptacle communication of the other; said first passageway opening to the atmosphere beyond said valves; and each of said valves carrying passageways thereacross to register in different valve positions with said passageways, to provide an open passageway from said pump intake connection through the head to said receptacle and simultaneously a passageway from said pump discharge 65 connection to the atmosphere; spring means normally positioning both of said valves to maintain said closed system closed off from both the atmosphere at the ends of said first passageway and closed off from said receptacle.

6. For checking sediment in fluids, a fluid sampling receptacle having means at its lower end for entrance therein of the fluid and filter means through which the fluid is discharged; a head attached to the receptacle and having normally a 5 passageway thereacross; an air pump having intake and discharge connections in spaced apart relation with said passageway, whereby said pump may operate in a closed system through the passageway; a second passageway across said head 10 having communication with said receptacle; intake and pressure control valves intercepting both of said passageways respectively between said intake and discharge connections of the one and on each side of said receptacle communication of the other; said first passageway opening to the atmosphere beyond said valves; and each of said valves carrying passageways thereacross to register in different valve positions with said passageways, to provide an open passageway from 15 said pump intake connection through the head to said receptacle and simultaneously a passageway from said pump discharge connection to the atmosphere; spring means normally positioning both of said valves to maintain said closed system closed off from both the atmosphere at the ends of said first passageway and closed off from said receptacle; said pressure valve in its normal 20 spring positioned position having its own passageways intercommunicating with said first head 25 30

passageway and said pump discharge connection; and said intake valve having its passageways providing an opening from said first head passageway to the atmosphere and from said second head passageway to said pump intake connection.

7. In a fluid sediment sampling device, the combination of a fluid receiving receptacle having a lower end intake opening; a head to which the receptacle is attached; an air pump having intake and outlet conduits connecting with said head; said head having passageways therethrough normally closed to said receptacle and in communication with said conduits whereby said pump may operate to circulate air in a closed system; intake valve means in said head intercepting said passageways; said head having a passageway leading from said receptacle to said valve means; and all of said passageways being arranged in said head to direct discharge from said pump through and externally of said head and receptacle and to provide a pump intake flow from said receptacle when said valve means is shifted from said closed system condition; and means automatically closing off said receptacle passageway upon fluid reaching a predetermined height in said receptacle as induced by flow in said system upon shifting of said intake valve means; said automatic means comprising a receptacle float operated valve in said receptacle passageway.

ADAM M. LANG.
